UNITED STATES PATENT OFFICE.

SENAT T. COOK, OF COWGILL, MISSOURI.

DITCHER AND GRADER.

Application filed June 28, 1922. Serial No. 571,468.

To all whom it may concern:

Be it known that I, SENAT T. COOK, a citizen of the United States, residing at Cowgill, in the county of Caldwell and State of Missouri, have invented certain new and useful Improvements in Ditchers and Graders, of which the following is a specification.

This invention relates to devices for forming ditches and grading roads and has for its object the provision of an inexpensive, strong and durable device which may be readily adjusted to form a ditch or to spread the loosened soil over the surface of the contemplated road so as to readily bring the road to the desired grade. The invention consists in certain novel features which are illustrated in the accompanying drawings and will be hereinafter first fully described and then particularly pointed out in the appended claims.

In the drawings:

Figure 1 is a plan view of an apparatus embodying my invention, indicating the same extended to extreme position in full lines and showing by dotted lines an intermediate position;

Fig. 2 is a side elevation;

Fig. 3 is a transverse section on the line 30 3-3 of Fig. 1;

Fig. 4 is a detail elevation of the rear end of the landside, and

Fig. 5 is a detail perspective view of the excavator point.

In carrying out my invention, I employ a bar 1 which may be of metal throughout or of wood as may be preferred, and constitutes the body of the share. This beam or bar 1 is set on edge, as clearly shown, and along its lower edge is secured a flat blade or plate 2 which is adapted to run along the surface of the ground and scrape the same, as will be readily understood. At the front end of the share, I secure an excavating point 3 which is a stout metal plate secured rigidly to the outer side of the member 1 and having its forward edge beveled so that it will readily penetrate the ground, as indicated at 4. This cutting edge 4 is also inclined upwardly and rearwardly, as shown clearly in Figs. 2 and 5. At the lower end of the point 3 is a horizontally extending lateral lip 5 which is adapted to extend under the soil at the side of the ditch and thereby facilitate the ex-

cavating. The landside 6 is similar in construction to the share 1 but is shorter than the share and is intended to have its lower edge 7 run out of contact with the bottom of the ditch, as will be readily understood upon reference to Figs. 3 and 4. To the outer side of the landside at the rear end portion of the same, I secure a short scraper blade 8 which is inclined downwardly toward its rear extremity, as shown most clearly in Fig. 4, so that as the device is drawn forward loose dirt behind the share will be permitted to sift or sift under the forward edge of the landside and will be spread evenly over the surface of the road, while at the rear portion of the landside, the quantity of dirt permitted to pass under the same will be gradually reduced and the desired crown formation attained, the short blade scraping the surface beyond the path of the point 3 and sharply defining the side of the ditch. Upon the upper edge of the landside, I secure a platform 9 which projects inwardly and abuts a transverse bracing beam 10 which is likewise secured upon the upper edge of the landside. Upon the upper edge of the share, near the rear end thereof, I secure a guide bracket or loop 11 through which one end of the brace 10 projects and through the brace I form a plurality of openings 12 which are arranged in an arcuate series concentric with the pivotal connection 13 between the landside and the share. A latch pin 14 is provided to be inserted through an opening in the bracket 11 and in one of the openings 12 to engage a socket 15 formed in the upper edge portion of the share, as clearly shown in Fig. 3. The share may thus be readily secured in any desired set position relative to the landside. To impart rigidity to the structure, a brace 16 is secured to the landside and to the beam 10 below the beam, and a similar brace 17 is secured to the share and projects laterally therefrom under the beam. Collapse of the beam while the device is in use is thus prevented.

To the inner side of the landside at the front extremity thereof and to the inner side of the share in rear of its front extremity, I secure similar brackets 18 and 19 which have their upper and lower extremities turned laterally, as shown at 20, and the pivot bolt 13 is inserted through the said laterally turned extremities and secured in position by any

convenient means. The share may thus be adjusted pivotally relative to the landside in an obvious manner.

Adjacent the upper edges of the share and the landside, I secure draft irons 21 having their forward extremities formed into hooks 22 which may be engaged by the rear links of draft chains 23 extending forwardly beyond the excavating point 3 and carrying 10 clevises 24 which may be coupled to a whiffletree 25 or to the draw-bar of a tractor, as will be readily understood. In using the device, draft is applied through the chains 23 and the members connected therewith so 15 that the scraper will be drawn forward over the line of the proposed ditch or over the surface of the road, as will be readily understood. When a ditch is to be formed, the share will be adjusted so as to lie close to the landside and the power or force of the device will, therefore, be concentrated at the 20 excavating point 3 so that it will readily cut through the ground and the walls of the cut will be pushed aside to the width desired in 25 the ditch. If the dirt turned out from the ditch is to be spread over the roadbed, the share is adjusted outwardly from the landside and the loosened upturned dirt will then be deflected more or less according to the adjustment of the wing and the grading and 30 crowning of the road will be accomplished. If the nature of the soil permits, the weight of the driver standing upon the platform 9 and the beam 10 will be sufficient to hold

the device to its work, but if the soil be of a 35 heavy tough quality, additional weights, such as large stones or other convenient objects, may be placed upon the beam so as to hold the grader down to the work.

My device is very simple in the construction and arrangement of its parts so that it is not apt to get out of order, and it is of such a form that it will very effectually resist the strains placed upon it and will prove very durable. 40

Having thus described the invention, what is claimed as new is:

1. In a grader, a share, an excavating point secured rigidly to the side of the share at the forward extremity of the same and having its front edge beveled and inclined upwardly and rearwardly and having a lateral horizontal lip extending along its lower edge on its outer face, and a flat scraper blade secured upon the side of the share in 50 rear of and abutting the point and extending to the rear end of the share.

2. A grader comprising a landside, a share pivotally connected with the landside, a short scraper secured in fixed position to the outer side of the landside at the rear end portion of the same and having its lower edge inclined downwardly and rearwardly, the lower edge of the landside being spaced from the ground and means for holding the share in 55 a set position relative to the landside.

In testimony whereof I affix my signature.
SENAT T. COOK. [L. s.]
